(57) **CLAIM**

The ornamental design for a conference board as shown and described.

DESCRIPTION

FIG. 1 is a front view of a conference board in accordance with the present invention;

FIG. 2 is a rear view of the conference board in FIG. 1;

FIG. 3 is a left side view thereof;

FIG. 4 is a right side view thereof;

FIG. 5 is a top view thereof;

FIG. 6 is a bottom view thereof;

FIG. 7 is a front perspective view of the conference board;

FIG. 8 is a rear perspective view of the conference board;

FIG. 9 is an enlarged view of a top portion as shown in FIG. 3;

FIG. 10 is an enlarged view of a bottom right portion as shown in FIG. 7;

FIG. 11 is an enlarged view of a top center portion as shown in FIG. 7;

FIG. 12 is a front view of another design of a conference board in accordance with the present invention;

FIG. 13 is a rear view of the conference board in FIG. 11;

FIG. 14 is a left side view thereof;

FIG. 15 is a right side view thereof;

FIG. 16 is a top view thereof;

FIG. 17 is a bottom view thereof;

FIG. 18 is a front perspective view of the conference board;

FIG. 19 is a rear perspective view of the conference board;

FIG. 20 is an enlarged view of a top center portion as shown in FIG. 12;

FIG. 21 is an enlarged view of a bottom right portion as shown in FIG. 12; and,

(Continued)

FIG. 22 is an enlarged view of a bottom left corner portion as shown in FIG. 18.

The broken lines in the drawings depict environmental structure and boundaries and form no part of the claimed design. Dashed lines in the drawings depict boundaries of regions shown in enlarged views and form no part of the claimed design.
